VENDING MACHINE

Bernard A. Hackett, Detroit, Mich.

Application April 12, 1935, Serial No. 15,974

5 Claims. (Cl. 312—66)

This invention relates generally to vending machines and more especially to a coin controlled type of machine adapted to dispense articles of merchandise such as cigarette packages and the like.

The principal object of the invention is to improve the art of dispensing merchandise.

It is also an object of the invention to provide a vending machine of the rotary stock carrier type in which the carrier cannot be rotated during operation of a coin slide so that merchandise cannot be broken or otherwise damaged so as to jam the machine.

Another object is to provide novel means for preventing the depression of a coin slide in the event that a package chute selected, has become empty.

A further object is to provide a novel coin display device adapted to facilitate detection of slugs, spurious coins, and the like, and to secure sufficient illumination of the coins displayed so that substitution may be readily detected.

Another object is to provide a novel arrangement of counter, coin slide, and magnifying coin display units in a vending machine.

Still another object is to provide means for preventing pilferage of merchandise from a vending machine.

Yet another object of the invention is to provide a novel rotary stock carrier construction including means for supporting advertising matter thereon.

Other objects, features and advantages will become apparent from the following description and appended claims.

For the purpose of illustrating the genus of the invention, typical concrete embodiments are illustrated in the accompanying drawings, in which:

Figure 1 is a front elevation, parts being broken away, of a vending machine constructed according to the principles of this invention;

Fig. 2 is a horizontal section, taken on the line 2—2 of Fig. 1;

Fig. 3 is a detail vertical section, taken substantially on the line 3—3 of Fig. 2;

Fig. 4 is a vertical section, taken substantially on the line 4—4 of Fig. 2;

Fig. 5 is a detail section, taken on the line 5—5 of Fig. 4;

Fig. 6 is a detail section, taken on the line 6—6 of Fig. 5;

Fig. 7 is a horizontal section, taken substantially on the line 7—7 of Fig. 4;

Figs. 8, 9 and 10 are detail sections, taken sub-

stantially on the lines 8—8, 9—9 and 10—10 of Figs. 7, 7 and 9, respectively; and

Fig. 11 is a fragmentary detail view, in side elevation, of a modified form of ejector mechanism.

Referring to the drawings, the vending machine, in general, includes a base unit 10 and a display unit 11.

The display unit 11 includes a transparent cylinder 12, preferably of glass, and upper and lower frame or header members 13 and 14 held in assembled relation by tie rods 15. As indicated in Figs. 4, 7 and 8, the display unit 11 is connected to base unit 10 by extending the tie rods 15 through suitable bayonets or keyhole-like openings provided at the upper margin of base 10, said openings including enlarged cylindrical portions 16 adapted to permit lock nuts 17 or other suitable head elements on rods 15 to be passed therethrough and slot portions 18 leading therefrom and adapted to receive the rods 15 but prevent passage of nuts or heads 17 therethrough.

Referring to Figs. 7 and 8, it will be noted that rotation of the display unit 11 in a counterclockwise direction, as viewed in Fig. 7, with respect to the base 10, will cause the bolt 15 to enter the slots 18 and the display unit and base unit may be locked together by means of a spring pressed detent 19 mounted in base 10 and projectable into a suitable opening 20 in bottom header 30 14 of the display unit 11. A chain 21 depends from the spring pressed detent 19 and extends to a point within the interior of base 10 and adjacent a lock door (not shown), whereby access is obtained to the chain 21 for the purpose of withdrawing the spring pressed detent 19 so that the display unit may be rotated in a clockwise direction, Fig. 7, and lifted from the base unit 10, the nuts 17 of tie rods 15 passing through the enlarged circular opening 16 of the keyhole openings. A change drawer 22, Fig. 9, is disposed within the base 10 adjacent the above mentioned lock door.

Within the display unit 11, a rotatable stock carrier 25 is arranged and comprises upper and lower spiders 26 and 27 carrying, and maintained in spaced relation by, stock chutes 28 and similar but smaller stock chutes 29. The stock chutes 28 are adapted to receive cigarette packages and the smaller stock chutes 29 for receiving boxes or other match containers, inturned flanges being provided at the bottom of each of said chutes to limit movement of the stock in a downward direction within the chute, as indicated in Figs. 2 and 4. The stock carrier 25 is fixed to a rod 31 55

5 journaled at the lower end thereof in a suitable standard 32 bolted to the bottom plate 33 of base unit 10. The upper end of rod 31 is journaled in the header or frame element 13. The intermediate portion of the rod 31 is of non-circular formation and engages correspondingly shaped openings in the spiders 26 and 27 so as to fix the stock carrier against rotation relative to rod 31. A hand wheel 34 is fixed to the upper end of the 10 rod 31 for rotating the stock carrier.

15 Referring more especially to Figs. 2 and 4, the bottom margin of a downwardly extending flange 35 provided on the spider 27 is shaped to form a corrugated cam surface 40 cooperable with a roller 41 for the purpose of aligning the cigarette package chutes 28 in the desired position with respect to a delivery chute 43 provided in the base unit 10. The roller 41 is carried by a plunger 44 mounted for reciprocation in a suitable bore 20 45 provided in the standard 32. A spring 46 is interposed between the plunger 44 and the bottom of bore 45 for maintaining the roller 41 yieldably in engagement with cam surface 40 on flange 35 of the lower spider 27. The stock carrier 25 25 may be rotated against the yieldable resistance afforded by the spring pressed roller 41 by means of the hand wheel 34; however, when the hand wheel is released, the spring urged roller 41 serves to position the nearest stock chute 28 in alignment with the delivery chute 43.

30 At the front of the vending machine and adjacent delivery chute 43, as indicated in Figs. 1 and 9, there is provided a vertically aligned and grouped arrangement of a register or counter 50, a coin slide 51 and a magnifying coin display 52. Thus all of the manual controls for the vending machine, are placed at readily visible points, the handle 34 for rotating the stock carrier being at the top of the device and the register 50, coin 35 slide 51 and magnifying coin display 52 being grouped adjacent the delivery chute 43. Also visible to a purchaser through the transparent cylinder 12 are the packages of merchandise, such as cigarettes, arranged within the stock 40 chutes 28, as indicated in Figs. 1 and 4, and advertising matter carried by the rotary stock carrier 25 in the form of advertising display cards 53 held to the stock chutes 28 by clip flanges 54.

45 The coin slide 51, per se, may be of any desired type, as, for example, a coin slide of the general type disclosed in the Hall Patent 1,908,752, issued May 16, 1933, and in the Tratsch Patent 1,908,380, issued May 9, 1933. It is noted, however, in the present instance, the coin slide 51 has a bracket 55 57 fixed thereto for operating the dispensing mechanism and associated parts of the vending machine.

50 Referring to Figs. 2 to 7 and 9, it will be noted that a vertically reciprocable lock bolt 55 is 60 mounted in a bearing 56 integral with or fixed to the support standard 32 and movable by means of a cam surface 47 formed on an upturned flange 48 provided on the bracket 57 which is fixed to the coin slide 51. Movement of the coin slide 65 51 inwardly of the vending machine causes the flange 48 to elevate the lock bolt 55 so that it enters one of a circular series of openings 49 provided in the lower spider 27 to lock the rotary stock carrier against rotation when the coin slide 70 51 is in an inwardly pressed position. One opening 49 is provided for each of the delivery chutes 28 and is positioned directly above the lock bolt 55 when one of the stock chutes 28 is positioned in alignment with the delivery chute 43. The 75 coin slide 51 is retracted by means of a spring 68

to an extended position with respect to the vending machine, as indicated in Figs. 7 and 9, causing retraction of the cam flange 48 and allowing the lock bolt 55 to drop and free the stock carrier for manual rotation. The projection of the lock 5 bolt 55 within one of the openings 49 upon inward movement of the coin slide 51, prevents a new selection of a different brand of packaged merchandise while the coin slide is in the inwardly pressed position so that packages will not 10 be broken and the machine jammed.

15 The bracket 57 also carries a package ejector 61 pivoted eccentrically with respect to its center of gravity to an upstruck lug 62 partially cut away from the bracket 57. Referring particularly to Fig. 5, it will be noted that the ejector 61 has a raised portion 36 adapted to be elevated upon rotation of the ejector about its pivotal connection to the lug 62 due to the overbalancing of the ejector by the heavy side thereof. The 20 ejector 61 has lateral portions 37 and 38, both downwardly sloping from the raised portion 36 so that the stock carrier 25 may rotate freely in either direction over the package ejector without interference from the latter. A hooklike element 25 30 63 is pivoted to the right hand end of the package ejector 61, as viewed in Fig. 5, on the heavy side of the ejector, so that when a package chute 28 is positioned over the ejector 61 and has become empty, the unbalanced weight of the ejector 61 rotates the same in a clockwise direction so that the element 63 can hook over a stationary element 64 fixed to the base unit 10. Thus, when an empty chute 28 is positioned above the ejector 61, the hook element 63 drops to a position such 35 that it will engage the stationary element 64 and limit movement of the coin slide 51 to a very slight reciprocation inwardly of the vending machine. The weight of the packages in chutes 28 normally maintains element 63 elevated and prevents engagement of the latter with stationary element 64. This prevents loss of coins in the event that the particular stock chute 28, positioned above the ejector 61, becomes empty.

40 A match packet ejector 65 is also pivotally connected to the flange 48 of bracket 57 so as to be reciprocated by the coin slide 51. The match packet ejector 65 is also pivoted eccentrically with respect to its center of gravity so that the heavier portion thereof will overbalance the same and normally rotate the ejector in a clockwise direction, as viewed in Fig. 6. A stud 66 is provided on the bracket 57 for limiting the rotation of ejector 65 in this direction, as indicated in Fig. 5. The match packet ejector is preferably arranged 45 radially outwardly of the stock chutes 28 and 29, as indicated in Figs. 4 and 6, so that there will be no interference between the ejector 65 and the stock carrier 25 upon rotation of the latter. When the coin slide 51 is pressed inwardly, the 50 package ejector 61 and match packet ejector 65 both ride along the bottoms of the articles to be ejected until the cam slide has been pushed back nearly to its rearmost position so that both ejector elements may then move back of the article 55 to be ejected, the lighter end portions of each ejector element being elevated so as to engage the article to be ejected upon retraction of the coin slide 51 to projected position by means of the spring 60.

50 Reference may now be had to Figs. 7 and 9 in which it will be noted that a lug 70 is also turned up from the rear margin of the bracket 57 carried by the coin slide 51 and is provided with an opening 71 which slidably receives a rod 71 connected 75

to the operating arm 12 of counter 50. The free end of the rod 11 is provided with a pair of lock nuts 73 and a spring 74 is disposed about the rod 11 between the lug 10 and lock nuts 73 to provide 5 a yieldable connection between lug 10 and rod 11 for actuating the counter or register 50 once upon each reciprocation of the coin slide 51. The spring 74 is provided to prevent breakage of the counter 50 in the event that the coin slide 51 10 is slammed to its inner position.

Referring to Figs. 9 and 10, the construction and operation of a coin handling chute 75 and the magnifying coin display 52 will be described. The coin chute 75 is restricted at two points, indicated at 76 and 77. A coin stop 80 is pivoted at 81 adjacent the rear or bottom wall of the chute 75 which is arranged in an inclined position. The coin stop 80 is generally sector shaped. As viewed in Fig. 9, the major portion of the weight of the 20 coin stop 80 lies to the right of the pivot 81 so as to maintain a stop bar 82 arranged tangentially of the periphery of the coin stop, against the underface of the forward or upper wall of the coin chute 75. The stop bar 82 normally lies 25 below and closes the lower end of the coin chute 75 so as to maintain previously deposited coins positioned immediately in rear of a window 83 in the forward or upper wall of the coin chute 75. The coin display unit 52 includes a magnifying 30 lens 85 spaced from the forward or upper wall of the coin chute 75 by a chamber 68 which includes angularly disposed and preferably curved walls 69, each having a light reflecting or mirror finish, so that any light entering the chamber 35 through the lens 85 will serve to illuminate coins positioned in rear of the window 83 at the restricted portion 77 of the coin chute 75. At the upper edge of the coin stop 80, two smaller sector shaped stop fingers 86 are provided and arranged 40 to project through suitable openings in the rear or under wall of the coin chute 75 when the coin stop 80 is rotated in a counter-clockwise direction, as viewed in Fig. 9, so as to close the chute 75 against the passage of coins past the restriction 76.

Prior to the inward reciprocation of the coin slide 51, the unbalanced weight of the coin stop 80 maintains the stop bar 82 in position to close the chute 75 at the restriction 77 and maintain 50 previously deposited coins immediately in rear of the window 83 so that these coins may be viewed in the display unit 52 as magnified by the lens 85. When the coin slide 51 is reciprocated, a chain 87 connected to the coin stop 80 55 and to coin slide 51, causes rotation of the coin stop 80 in a counter-clockwise direction about the pivot 81, as viewed in Fig. 9, so as to withdraw the stop bar 82 from its traversing position across the chute at the restriction 77 and releases the 60 coins held at this point, allowing the latter to be conveyed by the delivery end 88 of chute 75 to the coin drawer 22. Rotation of the coin stop 80 in such counter-clockwise direction rotates the stop fingers 86 to positions such that they traverse the chute 75 at the restricted portion 76, so that as coins are dropped from the coin slide 51, they will be held at the restriction 76. Retraction of the coin slide 51 by means of the spring 60 allows the coin stop 80 to swing back in 65 a clockwise direction so that the stop bar 82 closes the chute 75 at restriction 77 at the same time that the stop fingers 86 retract from the chute 75 to open the same at the restriction 76. This allows the coins just dropped by the coin 70 slide 51 to drop from the restriction 76 to the 75 slide 51 to drop from the restriction 76 to the

restriction 77 so that these coins will be displayed by the unit 52 as before.

Referring back to Fig. 4, light leaf or feather springs 90 and 91 are shown within the upper end of the delivery chute 43 and adjacent the 5 end of the package to be delivered. A spring 91 is provided for each of the chutes 28 and each spring serves to prevent jarring or rattling of packages out of the stock chutes 28 by tipping the vending machine forwardly and tapping the 10 base portion thereof against a supporting surface. A single spring 90 is mounted at the upper end of the delivery chute 43 and serves to tip the packages downwardly as they are delivered from the stock chute 28 to prevent jamming of packages at a restricted portion 92 provided in the delivery chute 43. The restriction 92 is provided to guard against theft of packages by reaching upwardly through the delivery chute 43. In addition, a pivoted guard or shutter 93 is hinged 15 at 94 to the forward margin of bracket 57 and provided with a cam flange 95 adapted to ride over the upper marginal edge of the under or back wall 96 of chute 43 so as to swing the guard or shutter 93 across the delivery chute 43 to prevent removal of packages from the vending machine while the coin slide 51 is inwardly pressed. 20

Reference may now be had to Fig. 11, which discloses a modified form of match package ejector 65' which may be made integral with the 30 flange 48 of bracket 57. In this embodiment the ejector 65' is rigidly fixed with respect to the bracket 57 rather than being pivoted so as to overbalance, as in the previously described embodiment. The rear margin 97 of the article engaging end of ejector 65' is beveled off to permit the coin slide 51 to be easily reciprocated to its inward position while the match packets contained within the stock chute 29 ride on the upper 35 end of the ejector 65'. 40

As many changes could be made in the above described construction, and many apparently widely different embodiments of this invention could be had without departing from the spirit thereof, it is intended that all matter contained 45 in the above description or shown in the accompanying drawings shall be interpreted as illustrative and not in a limiting sense.

What I claim is:

1. In a vending machine, a stock carrier 50 mounted therein for rotation about a vertical axis and including a plurality of vertically arranged stock chutes, a reciprocable coin slide, and means including an ejector element pivoted to said slide about an axis extending longitudinally of said 55 slide for dispensing articles of merchandise from a chute of said stock carrier, said ejector element being provided with downwardly inclined lateral margins for preventing interference with the rotation of said stock carrier. 60

2. In a vending machine, a stock carrier mounted therein for rotation about a vertical axis and including a plurality of vertically arranged stock chutes, a reciprocable coin slide, means including an ejector element pivoted relative to 65 said slide about an axis extending longitudinally of said slide for dispensing articles of merchandise from the chutes of said stock carrier, said ejector element being provided with downwardly inclined lateral margins for preventing interference with the rotation of said stock carrier, said ejector element being pivoted eccentrically with respect to its center of gravity whereby the ejector element rotates about its pivotal connection 70 to the coin slide so that a portion of the ejector 75

- is elevated to a position in back of an article of merchandise to be dispensed upon reciprocation of the coin slide a predetermined distance in one direction and removes one of said articles from 5 a stock chute upon reciprocation of the coin slide in another direction.
3. In a vending machine, a stock carrier mounted therein for rotation about a vertical axis and including a plurality of vertically arranged stock 10 chutes, a reciprocable coin slide, means including an ejector element pivoted eccentrically with respect to its center of gravity to said slide whereby said ejector element at the limit of reciprocation of said slide in one direction, rotates about its 15 pivotal connection to the slide so that a portion of the ejector element is elevated to a position in back of an article of merchandise to be dispensed and removes the said article from its stock chute upon reciprocation of the slide in the opposite direction, and means carried by said ejector element and engageable with a stationary part of said machine in the event that a stock chute has become empty to prevent reciprocation of said slide in said one direction.
- 20 4. In a vending machine, a stock carrier mounted therein for rotation about a vertical axis and including a plurality of vertically arranged stock 25 chutes, a reciprocable coin slide, means including an ejector element pivoted eccentrically with respect to its center of gravity to said slide whereby said ejector element at the limit of reciprocation of said slide in one direction, rotates about its pivotal connection to the slide so that a portion of the ejector element is elevated to a position in back of an article of merchandise to be dispensed and removes the said article from its stock chute upon reciprocation of the slide in the opposite direction, and means including a hook-like member pivoted to the ejector element on the heavier side of the latter and adapted to engage a stationary part of said machine when a stock chute becomes empty for preventing reciprocation 10 of said slide in said one direction.

5. In a vending machine, a delivery chute, a reciprocable coin slide and means operable thereby for dispensing articles of merchandise from said machine, a guard pivotally connected to said coin slide, cam means on said guard and engageable with a wall of said chute for swinging the guard to a position traversing said delivery chute upon reciprocation of said coin slide to prevent pilferage of merchandise from the vending machine during operation of the coin slide.

BERNARD A. HACKETT.
